PULL FOR A SLIDE FASTENER

Gerald F. Harlam, Providence, R.I., assignor to Pilling Chain Co., Inc., West Barrington, R.I., a corporation of Delaware

Filed May 31, 1967, Ser. No. 7,314

Term of patent 14 years

(Cl. D2—415)

FIG. 1

FIG. 2

FIG. 3

FIG. 4

FIG. 1 is a front elevational view of a pull for a slide fastener showing my new design, the side opposite being identical thereto;

FIG. 2 is a side elevational view thereof;
FIG. 3 is an enlarged top end view thereof; and
FIG. 4 is an enlarged bottom end view thereof.
The broken-line showing of a slider for a slide fastener is for illustrative purposes only.

I claim:

The ornamental design for a pull for a slide fastener, as shown and described.
